United States Patent Office.

BENJAMIN F. RICE, OF BOSTON, MASSACHUSETTS.

Letters Patent No. 65,273, dated May 28, 1867.

IMPROVED PORTABLE SHELF.

The Schedule referred to in these Letters Patent and making part of the same.

TO ALL WHOM IT MAY CONCERN:

Be it known that I, BENJAMIN F. RICE, of Boston, in the county of Suffolk, and State of Massachusetts, have invented an improved Portable Shelf; and I do hereby declare that the following is a full and exact description thereof, reference being had to the accompanying drawings and to the letters of reference marked thereon, of which—

Figure 1 is a perspective illustration, in which *a* is a block representing a section of a cook-stove on the right, with my improved shelf attached, and on the left a section of a ledge, *b*, attached to any article of furniture or fixture with another modified specimen of my improvement attached.

Figure 2 is a side view of my improvement applied to a ledge or strip attached to a wall or other fixture or article.

Figure 3 shows a specimen adapted for attachment or application to any ordinary strip or ledge which may chance to occur without bevelled or other particularly retaining edges.

Figure 4 is a side view, and

Figure 5 a front view of another specimen.

Like letters refer to the same or corresponding parts in all the figures.

c is the shelf or pan. To this is fixed an attachment, *i*, having the suitable-shaped end *d* to bear under a projecting part, as *e*. Another part, *f*, has an end, *g*, suited to bear upon the top of some object or article, and a lower part, *k*, adapted to bear against the side of such an object or article, or be adjusted with reference thereto by means of a screw, *h*. The part *i* is pivoted to the part *f* permanently by means of a journal or pin, *l*, or by means of lugs *m* on part *i*. Notches or sockets *n* and the lugs may, however, be reversed in order, the first being formed in part *i*, and the latter on part *f*, and of each there may be one, two, or more arranged for purposes of adjustment.

The use and operation of my improvement may be easily comprehended from the drawing. It is only necessary to lift the shelf or pan so as to cause part *d* to swing clear of part *e* to release the whole device from the object or article to which it is applied. So, also, to apply it to an object or article it is taken in the hand by the shelf or pan, part *g* adjusted to the top, and *k* to the side, passing part *d* under part *e*, and dropping down the pan or shelf, when it is secure and ready for use as a receptacle or support for such articles as it may be required for, whether as a lady's work-table, or the cook's cook-stove companion, or other of the multiplicity of uses to which it is adapted. A multitude of various designs, forms, and styles of finish will readily suggest themselves to the artisan as feasible and appropriate in the extended application of my improvement.

Having described my improvement, what I claim as my invention, and desire to secure by Letters Patent, is as follows:

Claim.

I claim pivoted or jointed parts *i d* and *g k*, in combination with a portable shelf or receptacle *c*, as a new article of manufacture.

BENJAMIN F. RICE.
